FIGURE 2 is a rear elevational view thereof;

FIGURE 3 is a side view thereof; and

FIGURE 4 is an underside plan view thereof.

The characteristic feature of my design resides in a grass edging blade having outer chamfered edges of arcuate form intersecting at the lower edge of the blade to define a point, and having an upper edge fashioned with straight tip portions and upwardly-opening semi-circular inner portions mounting a central vertical shank, which shank is coupled with a handle which is necked down for ferruled engagement with said shank.
